UNITED STATES PATENT OFFICE.

HARVEY J. SCHMELZER, OF KANSAS CITY, MISSOURI, ASSIGNOR TO E. I. HORSMAN CO., OF NEW YORK, N. Y., A CORPORATION OF NEW YORK.

DESIGN FOR A CHILD'S TOY BLOCK.

52,546.

Specification for Design.

Patented Oct. 8, 1918.

Application filed March 29, 1916. Serial No. 87,634. Term of patent 3½ years.

To all whom it may concern:

Be it known that I, HARVEY J. SCHMELZER, a citizen of the United States, residing at Kansas City, Jackson county, State of Missouri, have invented a new, original, and ornamental Design for Children's Toy Blocks, of which the following is a specification, reference being had to the accompanying drawing, forming a part thereof.

In the drawing, Figure 1 is a front elevation of a toy block, according to my invention, showing the front side thereof; Fig. 2 is a plan view of Fig. 1 looking from above; Fig. 3 is a view taken from the rear side of Fig. 1.

The block comprises a slab of any usual material bounded by flat surfaces at right angles to the faces of the slab so as to resemble, in general outline, a dancer in male attire with hands and feet laterally and oppositely extended. Lines and other ornamentation completing the representation are placed upon the two faces of the block.

I claim:—

The ornamental design for a child's toy block, as shown and described.

In testimony whereof I have hereunto set my hand.

HARVEY J. SCHMELZER.
